Patented Jan. 26, 1909.

UNITED STATES PATENT OFFICE.

ALOIS WILHELM MARIA EWERING, OF CASSEL, GERMANY, ASSIGNOR OF ONE-HALF TO HEINRICH DÜLFER, OF CASSEL, GERMANY.

TIME-RECORDER.

No. 910,517.

Specification of Letters Patent.

Patented Jan. 26, 1909.

Application filed May 23, 1906. Serial No. 318,311.

To all whom it may concern:

Be it known that I, ALOIS WILHELM MARIA EWERING, a subject of the German Emperor, residing at Cassel, Germany, have invented a new and useful Improvement in Time-Recorders, of which the following is a specification.

This invention relates to that class of time recorders in which a strip or ribbon of paper is moved by a clock work past an opening through which the ribbon or strip is exposed for writing the name of the person to be controlled upon the same, the opening being normally closed by a cover which is withdrawn 15 to uncover the opening when the name is to be written upon the strip and returned to its closed position when the signature has been made.

The object of this invention is to provide 20 convenient means for stopping the movement of the paper strip by the opening movement of the cover and releasing the strip by closing the cover.

In the accompanying drawings: Figure 1 25 is a sectional side elevation of a time recorder provided with my improvement. Fig. 2 is a sectional elevation showing parts of the mechanism on an enlarged scale, the clamping plate being shown released. Fig. 3 is a 30 similar vertical section through the clamping device, showing the clamping plate pressed against the strip. Fig. 4 is a section through the clamping device in line 4—4, Fig. 2. Figs. 5 and 6 are front and rear views of the 35 clamping device. Fig. 7 is a fragmentary face view of the recording strip.

Like letters of reference refer to like parts in the several figures.

A represents the case of the apparatus provided with a clock mechanism B which operates the feeding roll C by which the paper strip D is propelled in an upward direction from the lower roll E from which the strip is unwound. The strip is delivered from the 45 upper roll C into the lower portion of the case. The strip of paper is provided with divisions or marks arranged at such intervals and in such manner as may be required for effecting the desired control by recording the 50 name of the watchman, workman or other person upon the same. This strip passes through a clamping device which is arranged on the front side of the casing, preferably in an inclined position for conveniently writing

the name upon the part of the strip which is 55 exposed through the opening of the clamping device. The latter comprises a frame F having a passage f through which the strip passes upwardly and which has in its front portion an opening g through which a part of the 60 strip is exposed for writing upon the same. This opening is covered by a sliding cover H which moves in lateral ways h of the frame F and which is so constructed that the opening of the frame can be uncovered by moving the 65 cover to one side. The cover is preferably provided with an opening i which corresponds in size and form with the opening g of the frame, while the solid portion of the cover H covers the opening g of the frame 70 when the cover is closed. By moving the cover to one side the opening i of the cover is placed over the opening g of the frame and the strip is exposed through these openings.

The frame F is provided with a clamp K 75 which is arranged in the strip passage f of the frame F against the rear wall of the latter and which is movable toward and from the front wall of the frame. This clamp is operated by the sliding cover H, or otherwise 80 so connected with the same that when the cover is closed the clamp lies adjacent to the rear wall of the frame, as represented in Figs. 2 and 4, and leaves the strip free to move through the passage f, while by opening the 85 cover the clamp is pressed toward the front side of the frame and presses the strip against the same, as shown in Fig. 3, thereby stopping the movement of the strip and holding the latter stationary while the cover remains 90 open, thus permitting the signature to be placed conveniently and correctly upon the strip. The clamp consists, preferably, of a flexible or elastic plate of sheet metal which is secured at one end to the frame F and 95 which is pressed forwardly by a projection or incline l on the rear side of the cover H of the clamping device. This plate also serves as a convenient support or backing for the part of the strip on which the signature is 100 placed. Upon closing the cover the clamping plate releases the strip and the latter resumes its movement under the action of the clock mechanism.

The time at which the name was written 105 upon the strip of paper is indicated by the marks or divisions arranged upon the strip or ascertained by a separate scale with which

the strip can be compared. For illustration, if the watchman is required to enter his name upon the recording strip every half hour during his period of work, the marks or divisions 5 on the strip can be so arranged as to represent intervals of thirty minutes each, as indicated in Fig. 7. The time occupied in placing a signature upon the strip ordinarily does not exceed a few seconds and this period, 10 during which the strip is held against movement, is so small that the ordinary clearance of the teeth in the driving gear is sufficient to prevent the strip from getting out of register with the clock work. Even if the strip should 15 remain clamped for an excessive length of time it cannot be torn by the action of the clock work because the strip is driven by frictional contact and is capable of slipping on its driving wheel if prevented from moving with 20 the same.

I claim as my invention:

1. In a time recorder, the combination of a frame provided with a passage for the recording strip and with an opening through which 25 the strip is exposed, a movable cover for said opening, a movable clamping plate attached to said frame and having its free por-

tion arranged opposite said opening and adapted to be pressed against the rear side of the recording strip and form a clamp and back support therefor, and means on said cover for pressing said plate against the strip by opening the cover and releasing the plate from the strip by closing the cover, substantially as set forth. 30

2. In a time recorder, the combination of a frame provided with a passage for the recording strip and with an opening through which the strip is exposed, a sliding cover for said opening, a flexible clamping plate attached 40 to said frame and having its free portion arranged opposite said opening and adapted to be pressed against the rear side of the recording strip, and a projection on the sliding cover adapted to engage said plate and press 45 the same against the strip by opening the cover and releasing the plate from the strip by closing the cover, substantially as set forth. 35

Witness my hand this 5th day of May, 1906.

ALOIS WILHELM MARIA EWERING.
